UNITED STATES PATENT OFFICE

2,358,312

PARASITIC OSCILLATION ELIMINATION

George M. Brown, Scotia, N. Y., assignor to General Electric Company, a corporation of New York

Application May 29, 1943, Serial No. 489,008

5 Claims. (Cl. 179—171)

My invention relates to means for damping undesired oscillations in high frequency circuits, and is an improvement upon the invention described and claimed in U. S. Letters Patent No. 2,251,629 issued on August 5, 1941 to Laurence M. Leeds.

Amplifiers and other circuits operating at high frequencies frequently include arrangements of circuit elements or components such that leads or conductors of substantial length must be employed; such conductors have appreciable inductance and may resonate with capacities in the circuit to produce undesired parasitic oscillations. In accordance with the teachings of the aforesaid patent these undesired oscillations are effectively damped and minimized by providing a circuit including a condenser and a resistance in series connected to shunt the conductor; the resistance unavoidably includes inductance and this inductance is tuned with the condenser to series resonance at the undesired frequency. A purely resistive path is therefore provided for current at the undesired frequency. It has been found, however, in very high power amplifiers or other circuits that the heating loss in the shunting resistor at the fundamental frequency of the apparatus may be objectionably high. Accordingly, it is an object of my invention to provide an improved high power high frequency circuit in which undesired oscillations and resistance heating losses are minimized.

The features of my invention which I believe to be novel are set forth with particularity in the appended claims. My invention itself, however, both as to its organization and method of operation together with further objects and advantages thereof may best be understood by reference to the following description taken in connection with the accompanying drawing in which Fig. 1 illustrates schematically a high frequency push-pull amplifier embodying my invention, and Fig. 2 illustrates another embodiment of my invention.

The amplifier illustrated in Fig. 1 includes a pair of electron discharge devices 10 and 11 which are connected to operate in balanced or push-pull relation to amplify a signal or other high frequency wave from a source (not shown) which wave appears across an input inductance 12. The amplified wave is impressed across an output inductance 13 and is utilized in a suitable load circuit (not shown). The devices 10 and 11 include control electrodes or grids 14 and 15, respectively, connected to the ends of the input inductance 12. The devices 10 and 11 are provided with cathodes

16 and 17, respectively, which are connected to ground and with anodes or plates 18 and 19, respectively, connected to the ends of the output inductance 13.

The central point of the inductance 12 is connected to ground through a choke coil 20 and a battery or other suitable source of grid bias potential 21. A bypass condenser 22 is provided around the source 21. Condensers 23 and 24 are connected between the ends of the inductance 12 and ground and are selected so that their capacities, together with the unavoidable inter-electrode and circuit capacities, resonate with the inductance 12 at the frequency of the input signal wave impressed on the inductance.

In the output circuit the central point of the inductance 13 is connected to ground through a choke coil 25 and a suitable source of anode potential such as a battery 26, the battery being bypassed by a condenser 27. The condensers 28 and 29 are connected between the respective ends of the inductance 13 and ground and the capacity of these condensers, together with other capacities which are unavoidably present, are tuned with the inductance 13 to resonate at the frequency of the signal wave. Conventional neutralizing condensers 30 and 31 are provided to neutralize the anode-to-grid capacity effects of the devices 10 and 11. The condenser 30 is connected between the anode 18 of the device 10 and the grid 15 of the device 11 by a conductor 32. The condenser 31 is connected between the anode 19 and grid 14 by a conductor 33. At high frequencies the length of the conductors 32 and 33 is substantial and sufficient inductance is present so that it resonates with the interelectrode capacities of the devices 10 and 11 and with other inductance and capacity which is present in the circuit. The oscillations resulting from these resonant conditions may occur at frequencies either above or below the operating frequency of the amplifier. These undesired or parasitic oscillations may completely destroy the usefulness of the amplifier if they are sufficiently strong or they may produce erratic operation or spurious radiations and in any event they reduce the useful output of the amplifier. In accordance with the aforesaid Leeds patent the parasitic oscillations resulting from the presence of inductance in the conductors 32 and 33 are damped effectively by providing a series circuit shunting a sufficient length of the conductor and resonant at the undesired frequency so that it provides a pure resistance path for current at the undesired frequency. Series resonant circuits of this type

are employed in the amplifier illustrated in Fig. 1. The series resonant circuit shunting the conductor 32 comprises a resistance 34, unavoidably inductive, and a condenser 35 which tunes out this inductance at the undesired frequency. The series resonant circuit shunting the conductor 33 comprises an unavoidably inductive resistance 36 and a condenser 37 connected in series resonance at the undesired frequency.

In very high power, high frequency amplifiers it has been found that there may be substantial heating loss in the shunt resistors such as the resistances 34 and 36 due to the passage of current through these resistances at the fundamental operating frequency of the amplifier. These heating losses may be sufficiently high to overheat the resistors and it is, therefore, desirable that the heating be minimized.

I have found that these fundamental frequency heating losses may be minimized by providing inductances 39 and 40 in shunt with the condensers 35 and 37, respectively, and by tuning the condensers and the respective inductances in parallel resonance at the fundamental frequency. For example, the condenser 35 and inductance 39 comprise a tuning unit which is tuned to resonance at the fundamental frequency and, therefore, provides a high reactance path at the fundamental frequency and minimizes the passage of current at this frequency through the resistance 34. This reduces to a minimum the heating in the resistance 34 at the fundamental frequency. It is, of course, necessary to modify the series tuning of the inductance of resistor 34 and the capacity of the condenser 35 since the presence of the inductance 39 necessarily alters the constants of the circuit. I have found, however, that only two or three incremental adjustments of the condenser 35 and inductance 39 are necessary to provide a sufficiently close approximation to simultaneous series resonance at the undesired frequency and parallel resonance at the fundamental frequency. The inductance of the resistance 34, for example, is then in series resonance at the undesired frequency with the effective capacity of the tuning unit comprising the condenser 35 and the inductance 39.

It will readily be apparent that the combination of a resistance and a tuning unit as described above may be connected in shunt to a portion of any conductor in the circuit where undesired oscillations are present to damp these oscillations. For example, the damping circuit might be connected across portions of the anode or load conductors of the devices 10 and 11 indicated at 41 and 42, respectively, or across portions of the choke coils 20 and 25 or the neutralizing condensers 30 and 31.

The amplifier illustrated in Fig. 2 is similar to that shown in Fig. 1 and corresponding circuit elements have been designated by the same numerals; the electron discharge devices 10 and 11, however, are provided with screen grids or electrodes 45 and 46, respectively, conventionally located between the control electrodes and anodes of the respective tubes. These screen electrodes are employed to minimize the capacitive reaction between the anodes and control electrodes of the devices 10 and 11. The screen grids 45 and 46 are connected together and are connected to ground through a suitable source of potential indicated as a battery 47, suitable bypass condensers 48 and 49 being provided between the respective electrodes and ground.

In most amplifiers of the type illustrated when 78

screen electron discharge devices are employed, the action of the screens avoids the necessity of providing neutralizing condensers. However, when such screen electrodes are employed at very high frequencies it is sometimes difficult or impossible to ground them for the high frequency currents and consequently some feedback occurs to the control electrodes. For this reason in the circuit of Fig. 2 the neutralizing condensers 30 and 31 have been included together with the same parasitic oscillation damping circuits as are shown in Fig. 1.

Very high frequency parasitic oscillations frequently occur in amplifiers such as illustrated in Fig. 2. These oscillations may occur, for example, in a path through the plate or anode circuit of conductor 41, the discharge space between the anode 18 and the screen grid 45, through the condenser 48 to ground and thence through the condenser 28 back to the conductor 41. A corresponding circuit, of course, is present on the other side of the amplifier through the anode to screen-grid circuit of the device 11 and including a portion of the plate lead or anode conductor 42.

In order to eliminate these undesired high frequency parasitic oscillations, a series combination of a resistance 50 and a tuning unit including a condenser 51 and a shunt inductance 52 is connected in shunt to the conductor 41, and a similar series combination comprising a resistance 53 and a tuning unit including a condenser 54 and a shunt inductance 55 is connected in shunt to conductor 42. The effective capacity of the tuning unit including the condenser 51 and inductance 52 is tuned in series with the inductance of the resistance 50 to resonate at the frequency of the undesired oscillations and thereby presents a pure resistance path for currents at the undesired frequency. The resistance 50 may be adjusted to produce critical damping of the undesired parasitic oscillations so that such oscillations are effectively eliminated. The condenser 51 and inductance 52 are tuned in parallel resonance at the fundamental frequency of the amplifier in a manner similar to the tuning units in the neutralizing circuit. This minimizes the passage of current through the resistor 50 at the fundamental frequency and thereby minimizes or prevents undesired heating losses in the resistor. The shunt circuit comprising the resistor 53, condenser 54, and inductance 55 is tuned in a similar manner to minimize parasitic oscillations and fundamental frequency heating in the anode circuit of the device 11.

It will readily be apparent from the foregoing that I have provided a simple and effective arrangement which makes it possible to employ a series resonant circuit for damping parasitic oscillations and for minimizing resistance heating losses in the damping circuit due to the passage of current at the fundamental operating frequency of the apparatus.

While I have shown a particular embodiment of my invention in connection with push-pull amplifier circuits other applications will readily be apparent to those skilled in the art. I do not, therefore, desire to be limited to the particular arrangements and instrumentalities shown and described and I intend by the appended claims to cover all modifications which fall within the spirit and scope of my invention.

What I claim as new and desire to secure by Letters Patent in the United States is:

1. Radio apparatus comprising a circuit in which oscillations of an undesired frequency tend to exist, said circuit including a conductor of finite length, which thereby exhibits inductance across which such oscillations appear, and a resistance and a tuning unit serially connected between spaced points on said conductor, said tuning unit comprising a capacitor and an inductance connected in parallel, said resistance, due to its finite length, being inductive and being resonant at said undesired frequency with the effective capacity of said tuning unit, whereby a pure resistance is presented between said spaced points at said undesired frequency effectively to damp said oscillations, said tuning unit being tuned in parallel resonance at the fundamental operating frequency of said apparatus whereby passage of current through said resistance at the fundamental frequency is minimized.

2. In a high frequency power amplifier, two electron discharge devices each having an anode and a cathode and a control electrode, a circuit connected between said anode and control electrode and including a conductor of substantial length, said circuit having a tendency to break into oscillation at an undesired frequency, said conductor due to its length having substantial inductance, and a resistance and a tuning unit serially connected in shunt to said conductor, said tuning unit comprising a capacity and an inductance connected in parallel, said resistance being inductive due to its finite length and being resonant at said undesired frequency with the effective capacity of said tuning unit effectively to damp said oscillation, said tuning unit being tuned in parallel resonance at the fundamental operating frequency of said amplifier for minimizing the passage of current through said resistance at the fundamental frequency.

3. An electron discharge amplifier including a circuit which tends to oscillate at an undesired frequency, a portion of said circuit being a conductor of finite length whereby it is inductive, and a resistance and a tuning unit serially connected in shunt to said conductor, said tuning unit comprising a capacity and an inductance connected in parallel, said resistance being inductive due to its finite length and being series

5 resonant at said undesired frequency with the effective capacity of said tuning unit effectively to damp said oscillation, said tuning unit being tuned in parallel resonance at the fundamental operating frequency of said amplifier for minimizing the passage of current through said resistance at the fundamental frequency.

10 4. In a high frequency power amplifier having a triode electron discharge device and neutralizing means therefor, said neutralizing means including a conductor of substantial length the inductance of which tends to resonate with other portions of said amplifier at an undesired frequency, and means in shunt to said conductor for damping oscillations of said undesired frequency, said means comprising a resistance and a tuning unit connected in series, said tuning unit comprising a capacity and an inductance connected in parallel, said resistance being of finite length and exhibiting inductance, and the effective capacity of said tuning unit being of such value with respect to the inductance of said resistance as to resonate therewith at said undesired frequency effectively to damp said neutralizing means, said tuning unit being tuned in parallel resonance at the fundamental operating frequency of said amplifier for minimizing the passage of current through said resistance at the fundamental frequency.

20 5. In combination, an electron discharge amplifier device having an anode and a control electrode and a screen electrode, a circuit through said anode and said screen electrode including a conductor of finite length which thereby exhibits inductance, said circuit tending to oscillate at an undesired frequency, and a series combination of a resistor and a tuning unit in shunt to said conductor, said tuning unit comprising a condenser and an inductance connected in parallel, said resistor having finite length and exhibiting inductance and the effective capacity of said unit being resonant therewith at said undesired frequency effectively to damp said circuit, said tuning unit being tuned in parallel resonance at the fundamental operating frequency of said device for minimizing the passage of current through said resistor at the fundamental frequency.
